UNITED STATES PATENT OFFICE.

GEORGE B. BERGEN, OF MILWAUKEE, WISCONSIN.

PENCIL.

Application filed May 20, 1920. Serial No. 382,782.

To all whom it may concern:

Be it known that I, GEORGE B. BERGEN, a citizen of the United States, and resident of Milwaukee, in the county of Milwaukee, 5 and State of Wisconsin, have invented certain new and useful Improvements in a Pencil, of which the following is a specification.

My invention relates to pencils and particularly to a pencil adapted to be very economically manufactured.

One of the objects of my invention is to provide a pencil of the utmost simplicity, both as to manufacture and use, and one 15 which may be manufactured relatively very cheaply. In the pencil here disclosed I provide means for securely retaining short sections of lead and for feeding the lead by gravity following a very simple movement 20 of the tip. Means are also provided for readily removing the tip in order to enable the removal of any refractory leads which may become wedged or otherwise held within the lead tube.

25 A further object is to provide simple means for retaining the reserved supply of leads, such means being so constructed as to permit of the removal of but a single lead at one time and arranged whereby the single lead will not fall out but will merely project, permitting the grasping of the lead by the fingers. This element is so constructed that the desired action will take place in whatever position the pencil is 30 held. A further object is to provide a simple and practical form of an eraser-holder, the construction being such that the eraser may be caused to project the required distance beyond the holder as the rubber is 35 worn away.

The invention will be more readily understood by reference to the accompanying drawing in which:

40 Fig. 1 is a side elevation partly in section showing a pencil constructed in accordance with my invention;

Fig. 2 is a bottom plan view of one end thereof;

Fig. 3 is a sectional view somewhat enlarged on the line 3-3 of Fig. 1;

Fig. 4 is a sectional view on the line 4-4 of Fig. 1; and

Fig. 5 is a composite view showing the various parts in perspective, showing their 55 relative positions.

Figure 6 is a plan view of the cylindrical portion 20 of the tip showing the grooves 24, 25.

In the drawings it will be seen that I provide a body 10, which is preferably composed of wood, or other fiber, in order to give the required lightness. The body has a tapered end 11 provided with a concentric circular recess 12 therein. The formation of this recess results in the production of a reduced tapered portion 13 having a central longitudinal opening 14 therein. Within the recess 12 is mounted a sleeve 15 having a projection 16 which is pressed in the side thereof and also provided with a backwardly bent flange or skirt 17 which overlies the thinned edge of the wood, which surrounds the recess 12. Mounted within the central opening 14 is a split tube 18, of spring metal, having a slightly tapered end portion 19. Mounted within the sleeve is a tip having a cylindrical portion 20 and a tapered portion 21. The tip is hollow and the opening 22, in the end thereof, is of less diameter than the normal diameter of the tube 18 and of substantially the diameter of the leads employed, one of which is indicated at 23. The tip is provided with a helical groove 24, in the cylindrical portion thereof, and with a longitudinal groove 25 which communicates with the helical groove at the center thereof.

The arrangement is such that as the tip is pressed within the sleeve 15 the groove 25 is caused to register with the projection 16, thereby guiding the projection into the helical groove 24. During normal operation the tip is not removed but is merely rotated to clamp and release a lead by contracting and permitting the expansion of the slotted tube 18. However, should it become necessary to inspect the tube for the purpose of removing any leads which may have been retained therein the tip is rotated and pulled slightly. This will insure the engagement of the projection 16 with the exit portion of the groove 24 and permit of the ready removal of the tip.

The opposite end of the pencil is constructed to provide a cylinder 26 which is crimped as at 26^a into engagement with the wood body of the pencil, the cylinder having an open end. Mounted upon the cylinder is a sleeve 27, the end 28 of which is crimped into engagement with the groove 105 110

formed at 26^a by crimping the cylinder into engagement with the body. Both the cylinder and sleeve are provided with elongated slots 29, 30, adapted to be brought 5 into register by the rotation of the sleeve. These slots are of a width less than the diameter of two leads and thereby insure that but a single lead may be removed or inserted at one time. The slots are so positioned 10 with relation to the ends of the chamber and with relation to the length of the leads that when the pencil is tilted with the slots open the point of a single lead will drop through the opening but will not 15 fall out. This requires that the slots shall be properly positioned in the relation described.

In order to insure the tilting action I provide ledges on short transverse ribs 30^a, 20 30^b, at opposite ends of the slot 30 in the cylinder 26. It will be apparent that it is immaterial in which direction the pencil is tilted when a lead is to be withdrawn as the construction at both ends of the slot is 25 the same; a lead is shown in dotted lines in a reverse position to those in full lines.

The end 31, of the cylinder 26, is threaded as shown, and provides a seat or socket 30 for a rubber eraser, indicated at 32. A 30 threaded sleeve 33 surrounds the eraser and engages with the threaded end and by rotating this sleeve it will be seen that more or less of the eraser may be exposed as desired. It will be noted also that the eraser 35 forms the closure for the otherwise open end of the cylinder. This, however, may be varied, if desired, by providing an end wall for the cylinder.

Obviously modifications may be made in 40 the construction shown but I do not wish to be limited except as indicated in the appended claims.

I claim:

1. In a pencil, the combination of a slot-

ted fiber body having a tapered end, a relatively short slotted tube composed of spring metal and seated within a concentric aperture in said tapered end, and a conical tip mounted on said tapered end, the tip having an opening of less diameter than the normal diameter of said tip, the tube having a cam groove and a projection fixed with relation to said body and adapted to cooperate with the groove whereby to cause the tip to compress said slotted tube. 45

2. In a pencil, the combination of a body having a tapered end, a metal sleeve seated into said tapered end, said sleeve having a projection, a metal tube having a cylindrical portion adapted to fit within said 50 sleeve and provided with a helical groove and with a longitudinal groove communicating with the helical groove, said grooves being adapted to cooperate with said projection, and a slotted tube mounted within 55 the tapered end of the body, the tube being composed of spring metal and being adapted to be compressed by the rotation of the tip to clamp a lead within said tube, substantially as described. 70

3. In a pencil, the combination of a fiber body having a tapered end, the end being provided with a concentric circular recess, a metal sleeve mounted in said recess, a hollow tip having a cylindrical portion 75 adapted to be received within said sleeve, the tip and sleeve being provided with a cooperating groove and projection so constructed as to enable the removal of the tip, and a slotted tube mounted within the tapered end, the tube and tip being so constructed that a lead is adapted to be clamped within the tube by the rotation of said tip, substantially as described. 80

Signed at Chicago, Ill., this 4th day of 85
May, 1920.

GEORGE B. BERGEN.
